Primary Examiner — Charles D Hanson*(74) Attorney, Agent, or Firm* — Laurence A. Greenberg; Werner H. Stemmer; Ralph E. Locher(57) **CLAIM**

The ornamental design for a roll-up stretcher, as shown and described.

DESCRIPTION

FIG. 1 is a plan view of a pattern for the base plate for a roll-up stretcher showing my new invention;
 FIG. 2 is an elevation view of a head side thereof;
 FIG. 3 is an elevation view of a foot side thereof;
 FIG. 4 is a side view thereof, the two sides being mirror images of one another;
 FIG. 5 is a bottom plan view thereof; and,
 FIG. 6 is a perspective view of the roll-up stretcher having been formed into a stretcher trough, the shape of which is retained by the connection straps illustrated in dashed lines. The dashed lines in the drawings form no part of the claimed invention.
